UNITED STATES PATENT OFFICE.

MERRILL A. FURBUSH, OF PHILADELPHIA, PENNSYLVANIA, AND CHARLES H. KNOWLTON AND BENJAMIN F. MEYER, OF CAMDEN, NEW JERSEY, ASSIGNORS TO SAID MERRILL A. FURBUSH AND CHARLES A. FURBUSH, OF PHILADELPHIA, PENNSYLVANIA.

STOPPING MECHANISM FOR LOOMS.

SPECIFICATION forming part of Letters Patent No. 308,311, dated November 18, 1884.

Application filed October 1, 1883. (No model.)

To all whom it may concern:

Be it known that we, MERRILL A. FURBUSH, CHARLES H. KNOWLTON, and BENJAMIN F. MEYER, all citizens of the United States, said FURBUSH residing in Philadelphia, Pennsylvania, and said KNOWLTON and MEYER, residing in Camden, New Jersey, have invented certain Improvements in Stopping Mechanism for Looms, of which the following is a specification.

The object of our invention is to reduce the shocks and jars resulting from the stoppage of the movement of the lay when the shuttle fails to properly enter a shuttle-box; and this object we attain by providing the protector-shaft with an additional arm, which acts to effect the shifting of the belt onto the loose pulley before the other arm of the protector-shaft comes in contact with the stop on the breast-beam, so that the momentum only of the lay has to be arrested, there being no application of power thereto when the stop acts.

In the accompanying drawings, Figure 1, Sheet 1, is a side view of sufficient of a loom 25 to illustrate our invention; Fig. 2, Sheet 2, a view looking in the direction of the arrow 1, Fig. 1, the lay being omitted; and Fig. 3, Sheet 3, a plan view of part of Fig. 1.

A A' represent part of the side frames of 30 the loom, having bearings for the end driving-shaft, B, and for the crank-shaft D, the latter being connected to the lay E, and being driven from the shaft B by spur and bevel gearing in the usual manner. (See dotted lines, Fig. 1.)

The shaft B has fast and loose pulleys a a' for 35 receiving a belt from any adjacent counter-shaft, the belt being shifted from one pulley to the other by a fork, b, on a rod, d, guided in a bracket, e, on the frame A, and acted on 40 by a spring, f, which tends to draw the rod in the direction of the arrow and shift the belt from the fast pulley a to the loose pulley a'. The front end of the rod d is connected to one arm of a lever, F, hung to a pin on the 45 frame, the other arm of said lever being connected by a rod, g, to the long arm of a lever, G, secured to a rock-shaft, h, which is adapted to bearings on the breast-beam and frames of

the loom, and is at liberty to move longitudinally and also to turn in said bearings. The upper or short arm of the lever G has a lug, m, which is adapted to engage with a lug, m', on a lever, H, hung to a pin, e, on the frame A, a spring, v, tending to move the lever H in the direction of the arrow, Fig. 3, and thus retain the lug m' of the lever H in engagement with the lug m of the lever G, the driving-belt being under such circumstances upon the fast pulley a. When the lever H is moved in a direction contrary to that pointed out by the arrow, however, so as to free the lever G from the control of the lug m', the spring f causes the retraction of the rod d and the shifting of the belt from the fast to the loose pulley. This shifting of the belt must take place whenever 60 a shuttle fails to properly enter the box; hence the lay E carries a protector mechanism, which, as usually constructed, consists of a rock-shaft, i, extending across the lay, and having arms n and p, one arm n, being arranged near each end of the shaft, and each of said arms n having a lug, s, adapted to bear upon a shuttle-binder, k, in the front of one of the shuttle-boxes, so that when the shuttle enters the box the binder k will press the arm 70 n outward and depress the arm p, as shown by full lines in Fig. 1, the arm remaining in the elevated position shown by dotted lines when the shuttle fails to properly enter the box. One end of the shaft i and one arm, n, only are 75 shown in the drawings. When in the position shown by dotted lines, the arm p on the forward movement of the lay strikes a stop on the breast-beam and prevents the lay from beating up, otherwise the shuttle remaining 80 in the shed would break the warp-threads. In the usual construction the arm p has also been caused to effect the shifting of the belt from the fast to the loose pulley, said arm striking a lever, which presses the shipper-handle out of its notch and causes the necessary movement of the belt just before the movement of the lay is arrested by contact of the arm p with the stop or bunter. The objection to this plan is that the operations follow 85 each other so closely that the belt cannot be 90 95

fully shifted before the contact of the arm with the stop; hence the forward movement of the lay is arrested while power is still being applied to cause such movement, and in consequence sudden shocks and a severe straining of the loom result. We overcome this objection by providing the protector-shaft *i* with an additional arm, *x*, which acts in advance of the stop-arm *p*, so that ample time is afforded for fully shifting the belt before the movement of the lay is arrested. The arm *x* has a cam-like outer end adapted to strike the downwardly-bent end of the lever *H*, and cause the vibration of said lever, so as to withdraw its lug *m'* from engagement with the lug *m* of the lever *G*. A lever, *J*, is hung to the lever *G*, and a lever, *J'*, to an arm, *y*, on the shaft *h*, the short arms of the lever being adapted to slots in the frame *A*, so that by manipulating either of the levers a longitudinal movement of the shaft *h* against the action of a spring, *h'*, may be effected, this movement being sufficient to free the lug *m* of the lever *G* from engagement with the lug *m'* of the lever *H*, the latter being retained by contact with a stop, *v'*, on the frame. The

loom can thus be thrown out of gear by hand from either side, or the release of the lever *G* may be effected by operating the lever *H* by hand.

30

We claim as our invention—

1. The combination of the lever *G* and the belt-shifting devices of the loom connected to said lever, the lay *E*, the shuttle-boxes, the breast-beam, the lever *H*, having a lug adapted to engage with and retain the lever *G*, and the protector-shaft having a stop-arm, *p*, and an arm, *x*, adapted to strike and cause the vibration of the lever *H*, as set forth. 35

2. The combination of the lever *G*, the arm *y*, the shaft *h*, the spring *h'*, the levers *J J'*, the slotted frame *A A'*, and the lever *H*, as set forth. 40

In testimony whereof we have signed our names to this specification in the presence of 45 two subscribing witnesses.
